CARRYING HANDLE FOR CONTAINERS

Daniel Belcher, Minneapolis, Minn., assignor to
 Bemis Bro. Bag Co., Minneapolis, Minn., a corporation of Missouri

Application March 18, 1935, Serial No. 11,586

13 Claims. (Cl. 229—54)

This invention relates to new and useful improvements in carrying means for small containers or bags of the general character shown and described in my pending application, Serial 5 No. 5,065, filed February 5, 1935.

An object of the present invention is to provide a simple and inexpensive carrying means for containers, particularly, paper bags having their upper wall portions folded inwardly, one 10 over the other, to provide a closure for the bag top, which may readily and conveniently be attached thereto without necessitating any changes in the operation of closing and sealing the bag tops.

15 A further object is to provide a carrying handle for paper bags comprising a carrying handle having plate elements secured to the terminals thereof and adapted for relative movement thereon, whereby said plate elements may be fitted between the folds of the bag top walls, thereby to detachably secure the carrying handle to the bag top.

20 A further object is to provide a novel carrying means for sealed bags, comprising a flexible handle member having plate elements secured to the ends thereof adapted to be fitted between the folded walls of the bag top, and resilient means being provided for holding said plate elements in operative positions when the carrying means 25 is attached to the bag top.

Other objects of the invention will appear from the following description and accompanying drawings and will be pointed out in the annexed claims.

30 In the accompanying drawings there has been disclosed a structure designed to carry out the various objects of the invention, but it is to be understood that the invention is not confined to the exact features shown as various changes may 35 be made within the scope of the claims which follow.

In the drawings:

Figure 1 is a perspective view showing my improved carrying handle attached to a bag top; 45 Figure 2 is a perspective view showing the preferred manner of folding the walls of the bag top, whereby the plate elements of the carrying handle may readily be inserted between the folded wall portions of the sealed bag top;

50 Figure 3 shows one of the plate elements in operative position on the sealed bag top;

Figure 4 shows the second plate element partially inserted between the folds of the bag top;

55 Figure 5 shows both plate elements in operative positions between the folded bag top walls

to thereby detachably secure the handle to the bag;

Figures 6 is a view showing the carrying handle detached from the bag;

Figure 7 is an enlarged detail sectional view 5 on the line 7—7 of Figure 5, showing one method of securing the terminals of the wire handle to the plate elements;

Figure 8 shows a slightly modified construction 10 in which the plate elements may be constructed of cardboard having wire staples for securing the terminals of the handle thereto;

Figure 9 is an enlarged detail sectional view 15 on the line 9—9 of Figure 8;

Figure 10 shows another construction in which 20 the carrying handle is shown composed of a flexible fabricated material such as a suitable tape, having its terminals secured to plate elements adapted to be secured to the folded wall portions of the bag top; and

Figure 11 is a perspective view showing the manner of attaching the handle shown in Figure 25 10 to the bag top.

The novel carrying handle disclosed in Figures 1 to 9, inclusive, is shown comprising a wire handle 2 having spaced legs 3 provided with inwardly turned terminals 4. The handle 2 is preferably constructed of spring wire, whereby it may readily be flexed without becoming permanently distorted.

Suitable plate elements 5 are detachably and 30 pivotally secured to the terminals 4. In Figures 1 and 3 to 7, inclusive, I have shown the plate elements 5 provided with upwardly bent portions 6, which form eyes 7, adapted to receive the terminals 4, as clearly illustrated in Figure 1. In the present instance, the upwardly bent portions 6 are shown struck from the material from which the plate elements are made. The plate elements 5 are preferably made from sheet metal, although 35 it is to be understood that they may be made from other material suitable for the purpose.

The terminals 4 of the handle 2 are shown provided with projections 8 which are spaced apart to receive therebetween the upwardly bent portions 6 of the plate elements 5, as clearly illustrated in the drawings. The main portion of the handle 2 and the terminals 4 are of such length that when the plate elements are positioned on the terminals 4, as shown in Figure 3, and one of 40 said elements is inserted between the folds of the bag top, the other element, as shown at the right-hand side of Figure 3, will be so positioned with respect to the folds of the bag top, that it may readily be inserted therebetween without mate- 45 50 55

rially flexing the handle portion 2. The plate element at the right-hand side of Figure 3 is then inserted between the folded bag top walls, as shown in Figure 4, until it reaches substantially 5 the position shown in Figure 5, wherein it will be noted that the upwardly bent portions 8 of the plate elements 5 are engaged with the inner ends of the terminals 4 between the offset portions or 10 projections 8-8 of each terminal. When thus positioned, the offset portions 8 of said terminals prevent the handle from accidentally becoming detached from the plate elements 5, when the handle is in the position shown in Figure 1.

In the form here shown, the handle 2 may be 15 folded flatly against a bag top, as shown in Figure 5, when not in use. If desired, the plate elements 5 may be provided with suitable spurs 9 formed by partially piercing the material with a suitable instrument, whereby the upturned spurs 20 9 are formed, as clearly illustrated in Figure 7. These spurs engage the under surfaces of the flaps 8 of the folded bag top, and prevent the plate elements from accidentally becoming detached from the bag top, when the bag is being 25 carried by the handle 2.

Figures 8 and 9 illustrate a carrying means in which the handle 2 is secured to the bag top by plate elements 10 having staples 11 providing eyes adapted to receive the terminals 4 of the handle 2, as clearly illustrated in Figure 8. The plate elements 10 are preferably constructed of cardboard and may be provided with suitable tacks 12 permanently secured thereto, and having their terminals 13 projecting above the upper surfaces 30 of the plate elements 10, whereby they may engage or pierce the walls of the bag top, thereby to prevent the plate elements from accidentally becoming detached from the bag top.

The form shown in Figures 10 and 11 comprises 40 a carrying handle 14 of a suitable flexible material, such as fabricated tape, having its ends suitably secured to plate elements 15 by stitching or stapling, as indicated at 16 in Figure 10. An elastic band 17 has its end portions suitably 45 secured to the plate elements 15, preferably at the locations where the ends of the handle 14 are secured thereto. The elastic band is of such length as to retain the plate elements 15 in operative positions, as shown in Figure 10, when the 50 handle is attached to the bag top. The band 17 may readily be stretched, as shown in Figure 11, to permit the plate elements to be inserted between the folds of the bag top, as will readily be understood by reference to the drawings. Suitable spurs 18 are shown provided in the plate elements 15, to prevent the latter from becoming detached from the folded bag top, when the handle 55 is attached thereto.

The carrying handle, shown in Figures 10 and 60 11 may be folded against the bag top when not in use, because of the flexible nature of the material from which the handle portion 14 is made. It is simple and inexpensive in construction and may readily and quickly be attached to the bag 65 tops in the manner shown.

I claim as my invention:

1. A carrying handle for bags or containers 70 adapted to be detachably secured to the closed tops thereof, said carrying handle comprising a handle portion having inwardly turned terminals, and plate elements movably supported on the terminals and movable towards and away from one another to facilitate attaching the handle to the bag top.

75 2. A carrying handle adapted to be detachably

secured to the closed tops of paper bags, said handle comprising a handle portion having inwardly turned terminals, plate elements having sockets therein for receiving the terminals, said plate elements being movable towards and away from one another on said terminals, thereby to facilitate attaching the handle to the bag top. 5

3. A carrying handle adapted to be detachably secured to the closed tops of paper bags, said handle comprising a handle portion having inwardly turned terminals, said handle and terminals being disposed in the same plane, and plate elements movably supported on the terminals and movable towards and away from one another to facilitate attaching the handle to the bag top. 15

4. A carrying handle for paper bags or containers whose top wall portions are folded inwardly over the bag body, one over the other, said handle comprising plate elements adapted to be inserted between the folded wall portions of the bag top to secure the handle thereto, said plate elements being adjustable lengthwise of the handle whereby they may be attached to the bag closure substantially without flexing the handle. 20

5. A carrying handle for paper bags comprising 25 a one-piece handle portion having terminals disposed in spaced parallel relation thereto, projections on said terminals spaced apart lengthwise thereof, plate elements having sockets for receiving said terminals, and adapted to be inserted between the folds of the closed bag top to secure the handle thereto, the projections on said terminals preventing the handle from becoming disengaged from said plate elements when said handle is in operative position. 30

6. A carrying handle for paper bags comprising 35 an one-piece handle portion having inwardly turned terminals disposed in spaced parallel relation thereto, projections on said terminals spaced apart lengthwise thereof, plate elements 40 having sockets for receiving said terminals, and adapted to be inserted between the folds of the closed bag top to secure the handle thereto, the projections on said terminals preventing the handle from becoming disengaged from said plate elements when said handle is in operative position. 45

7. A carrying device comprising a pair of plate elements connected together by a resilient member, whereby when said plate elements are inserted between the folds of a closed bag top, said resilient member will retain the carrying device 50 in operative position on the bag top.

8. A flexible carrying handle comprising a pair 55 of plate elements connected together by a stretchable member, whereby when said plate elements are inserted between the folds of a closed bag top, from opposite sides of the bag top, said stretchable member will retain them in operative positions between said folds. 60

9. A carrying handle comprising a flexible handle member adapted to be grasped by the 65 hand, plate elements secured to the ends of said handle member and adapted to be inserted between the folded wall portions of a closed bag top thereby to secure the handle to the bag, and an elastic member secured to said plate elements 70 and constantly urging them between the folded wall portions of the bag top, thereby to retain the plate elements in operative positions on the bag closure. 75

10. A carrying handle for paper bags whose 80

top wall portions have been folded inwardly over the bag body, one over the other, and having portions gummed to secure them in bag-closing relation, said handle comprising a flexible member 5 adapted to be grasped by the hand and having means secured to the ends thereof adapted to be inserted between the ungummed wall portions of the closed bag top to thereby secure the handle thereto.

10 11. A carrying handle for paper bags whose top wall portions have been folded inwardly over the bag body, one over the other, and having portions gummed to secure them together in bag-closing relation, said handle comprising a flexible member 15 adapted to be grasped by the hand, means secured to the ends thereof adapted to be inserted between ungummed portions of the walls of the closed bag top to thereby secure the handle to the bag top, and means for preventing said 20 first-mentioned means from accidentally becoming detached from the bag top.

12. A carrying handle comprising a flexible handle member adapted to be grasped by the hand, plate elements secured to the ends of said handle member and adapted to be inserted between the folded wall portions of a closed bag

top thereby to secure the handle to the bag, an elastic member secured to said plate elements and constantly urging them between the folded wall portions of the bag top, thereby to retain the plate elements in operative positions on the bag closure, and means on said plate elements for preventing relative movement thereof, when operatively engaged with a closed bag top. 5

13. A carrying handle for paper bags comprising a flexible handle member adapted to be 10 grasped by the hand, plate elements secured to the ends of said handle member and adapted to be inserted between the folded wall portions of a closed bag top to secure the handle to the bag, an elastic band secured to said plate elements 15 and constantly urging them between the folded wall portions of the bag top, thereby to retain the plate elements in operative positions between the folds of the bag top, and suitable spurs on the upper faces of the plate elements adapted to engage the folded wall portions of the bag top to thereby prevent said plate elements from accidentally becoming displaced, when in operative 20 positions on the bag top.

25

DANIEL BELCHER.
